CLAIM

The ornamental design for a communication device, as shown and described.

DESCRIPTION

FIG. 1 is a top perspective view of a communication device showing a first embodiment of our new and ornamental design;

FIG. 2 is a front elevation view thereof;

FIG. 3 is a rear elevation view thereof;

FIG. 4 is a side elevation view thereof;

FIG. 5 is an alternate side elevation view thereof;

FIG. 6 is a top plan view thereof;

FIG. 7 is a bottom plan view thereof;

FIG. 8 is a top perspective view of a communication device showing a second embodiment of our new and ornamental design;

FIG. 9 is a front elevation view thereof;

FIG. 10 is a rear elevation view thereof;

FIG. 11 is a side elevation view thereof;

FIG. 12 is an alternate side elevation view thereof;

FIG. 13 is a top plan view thereof;

FIG. 14 is a bottom plan view thereof;

FIG. 15 is a top perspective view of a communication device showing a third embodiment of our new and ornamental design;

FIG. 16 is a front elevation view thereof;

FIG. 17 is a rear elevation view thereof;

FIG. 18 is a side elevation view thereof;

FIG. 19 is an alternate side elevation view thereof;

FIG. 20 is a top plan view thereof; and,

FIG. 21 is a bottom plan view thereof.

(Continued)

The portions of the communication device shown in broken lines in the figures attached hereto form no part of the claimed design.

1 Claim, 21 Drawing Sheets
